MANUFACTURE OF ENVELOPES AND MACHINE THEREFOR

Vincent E. Heywood, Worcester, Mass., assignor
to United States Envelope Company, Spring-
field, Mass., a corporation of Maine

Application September 14, 1931, Serial No. 562,695

5 Claims. (Cl. 93—61)

The present invention relates to the manufacture of envelopes, and has for its object the provision of instrumentalities for making completed envelopes from previously cut blanks or sheets, at a high rate of production, and with extreme uniformity and perfection in the resulting product.

The manufacture of envelopes in accordance with the present invention is particularly characterized by folding the side flaps of a previously scored and gummed blank over forms with which the lines of scoring are accurately gaged, the forms thereafter cooperating with bottom flap folding means to complete the envelope. As a result of the correlated scoring, gaging and folding operations, envelopes of a superior quality are produced, from any grade of paper, with sharp clean edges and corners and of absolutely uniform character. The above and other advantageous features of the invention will hereinafter more fully appear from the following description with reference to the accompanying drawings illustrating one arrangement of instrumentalities for carrying out the invention, in which:—

Fig. 1 is a view in side elevation of a portion of an envelope machine embodying the invention.

Fig. 2 is a top plan view of the mechanism shown in Fig. 1.

Fig. 3 is a diagrammatic view based on Fig. 1, illustrating the gearing for driving the mechanism shown.

Fig. 4 is a fragmentary view of one of the side flap folding mechanisms.

Fig. 5 is a fragmentary view illustrating a portion of the parts of the bottom flap folding mechanism.

Fig. 6 is a fragmentary view similar to Fig. 5, illustrating the parts in a different position.

Like reference characters refer to like parts in the different drawings.

Referring first to Figs. 1 and 2, the mechanism constituting the present invention is shown as being supported between spaced side frames 1, 1 extending longitudinally of the machine and which afford suitable bearings for several shafts extending between the frames. One such shaft is the main driving shaft 2, which is adapted to be driven from any suitable source of power, not shown, by means of a belt or driving chain 3, as indicated. As best shown in Fig. 3, the driving shaft 2 carries a gear 4 in mesh with a gear 5 on a shaft 6 extending above and parallel to the shaft 2, so that the shafts 2 and 6 rotate in opposite directions and at the same speed. The shafts

2 and 6 carry cooperating scoring rolls 7 and 8 respectively, Fig. 1, the construction of which will be hereinafter described with relation to associated mechanism of the machine.

The gear 4 on the drive shaft 2 is in mesh with a gear 9 on a shaft 10 carrying a roll 11, a portion of the periphery of which is engaged by a plurality of endless belts or tapes 12, spaced from the periphery of the lower scoring roll 7 by guide rolls 13, see Fig. 1. From the lower portion of the roll 11 the tapes 12 pass around a roll 14 mounted on a shaft 15 that is driven through a train of gears 16, 16 from the gear 9 on the shaft 10. From the tape driving roll 14, the tapes 12 pass upwardly around a guide roll 17, a portion 15 of each tape 12 being substantially horizontal between its points of tangency to the guide roll 17 and the uppermost guide roll 13. Consequently, the tapes 12, moving in the direction of the arrow of Fig. 1, are adapted to convey envelope blanks in their flat or extended condition in the direction of the bight between the scoring rolls 7 and 8, the actual delivery of each blank to the scoring rolls being under the control of a pair of movable stops 18 and gaging fingers 19, the operation of which will be hereinafter described. The envelope blanks may be fed or delivered, one by one, to the moving belts or tapes 12 by any suitable mechanism commonly found in machines of this class, the details of which mechanism form no part of the present invention, and hence are not shown herein.

The roll 14 for driving the tapes 12 also serves to drive a plurality of tapes 20 extending horizontally in alignment with the horizontal portions of the tapes 12 between the points of tangency of the rolls 11 and 14. The tapes 20 pass around a front guide roll 21 with the ends of the tapes 20 spaced from a pair of delivery rolls 22. The moving tapes 20 are adapted to deliver an envelope into the bight between the rolls 22 under the control of a pair of stops 23 and gaging fingers 24 cooperating with a folding mechanism, hereinafter to be described.

As indicated by the arrow in Fig. 1, each envelope blank delivered to the tapes 12 is adapted to be arrested in its movement toward the scoring rolls 7 and 8 by means of the stops 18, the gaging fingers 19 serving to register each blank 25, as indicated in Fig. 2, before release of the blank by the stops 18 permits the envelope to be projected into the bight between the rolls 7 and 8. Simultaneous rotation of the rolls 7 and 8 in opposite directions causes the blank 25 to be scored along the desired line of folding be-

tween the flaps 25a and the body of the blank. As the scoring is completed, a guide 26 cooperating with the lower scoring roll 7 serves to direct the scored blank around the roll 7 into the bight between the roll 7 and the roll 11, and from thence to the moving tapes 12.

As the scored envelope blank 25 passes around the periphery of the roll 11 in contact with the tapes 12, adhesive is applied to the extended flaps 25a of the blank in any suitable manner, as by means of a roll 27 providing adhesive applying projections 28, the roll 27 being mounted on a shaft 29 carrying one of the gears 16, see Fig. 3. Liquid adhesive is supplied to the roll 15 27 from a suitable reservoir 30, in which is rotatably mounted a roll 31 having its periphery in contact with a second roll 32, which applies the adhesive to the projections 28 of the roll 27. Obviously, any other suitable mechanism may be employed for applying adhesive to the flaps 25a of the envelope blank 25.

Upon leaving the periphery of the roll 11 with the adhesive applied to its flaps, the blank 25 travels in a substantially horizontal plane and 25 passes from the tapes 12 to the tapes 20 until its movement toward the rolls 22 is arrested by the stops 23, which as best shown in Fig. 2, engage the corners of the blank at the intersections of the side flaps 25a with the bottom flap 30 25b. At this moment, the blank is also acted upon by the gaging fingers 24 which operate from the other side of the blank to engage the corners thereof at the intersections of the side flaps 25a with the sealing flap 25c. Consequently, the parallel lines of scoring along the junctions of the side flaps 25a with the body of the blank are brought into exact alignment with the parallel edges of a pair of spaced folding forms 33, beneath which the blank passes as it is moved 40 to engage the stops 23.

As will be hereinafter described in detail, the projecting side flaps 25a of the blank thus positioned are then folded over the edges of the forms 33 by means of folders 34 operating from 45 opposite sides of the blank, see Fig. 4, the line of folding of each flap corresponding exactly with the line of scoring on the blank. Following this, the bottom flap 25b is folded along the line of scoring between the flap 25b and the blank 50 body by means of a folder 35, the folding operation being completed by travel of the blank into the bight between the rolls 22, as illustrated in Figs. 5 and 6, after release of the blank by the stops 23. The folding of the bottom flap 25b 55 along the line of scoring is assured by the positioning of the end surfaces of the folding forms 33 in alignment with the line of scoring between the flap 25b and the blank body, as indicated in Fig. 2, the forms 33 being afterwards utilized to 60 project the folded blank into the bight between the rolls 22. As the folded blank passes between the rolls 22, the overlapping edges of the side flaps 25a and bottom flap 25b are pressed closely together so as to secure the flaps tightly together, 65 due to the adhesive therebetween. Having thus generally outlined the progress of an envelope blank through the machine, and having identified the several instrumentalities operating on each blank for first accurately gaging and scoring the blank, next applying adhesive, then again gaging the scored blank, and finally folding its flaps exactly along the lines of the scoring to produce a complete envelope, the details of construction and operation of these instrumentalities will now 70 be described.

The pair of stops 18, which serve to bring each blank to rest as it is moved by the tapes 12 toward the scoring rolls 7 and 8, are adjustably mounted on a shaft 36 extending between the side frames 1, 1, the position of each stop 18 being 5 determined by a set screw 37 cooperating with the shaft 36. The gaging fingers 19 are similarly mounted on a shaft 38 extending parallel to the shaft 36, set screws 39 determining the position of the fingers 19 on the shaft 38. Obviously, the 10 stops 18 and fingers 19 can be positioned on their respective shafts 36 and 38 in order to obtain the proper spacing therebetween to engage accurately with the four corners of an envelope blank 25, as indicated in Fig. 2. 15

The shaft 36 carrying the stops 18 is adapted to have an oscillatory movement imparted thereto by means of a crank arm 36a pivotally connected to a link 40 terminating at its end in a yoke portion embracing the shaft 2. As indicated in dotted lines in Fig. 1, the link 40 carries a roll 41 bearing on the surface of a cam 42 mounted on the shaft 2. The cross-shaft 38 carrying the gaging fingers 19 is similarly provided with a crank arm 38a pivotally connected to a link 43 25 providing a yoke portion embracing the upper scoring roll shaft 6. The shaft 6 carries a cam 44 upon which bears a roll 45 carried by the link 43, so that the oscillatory movement of the shafts 36 and 38 are in timed relation to the rotation 30 of the scoring rolls 7 and 8. The timing of the cams 42 and 44 is such that as an envelope blank 25 approaches the scoring rolls, the stops 18 are turned downwardly into the position shown in Fig. 1 to arrest the movement of the blank 25 35 by the tapes 12. As the envelope blank comes to rest, the gaging fingers 19 are also swung downwardly to accurately align the blank, so that there is a dwell in the movement of the blank toward the scoring rolls 7 and 8, during which 40 the blank is accurately gaged, as shown in Fig. 2.

With the stops 18 and gaging fingers 19 in the position shown in Fig. 1, the upper scoring roll occupies a position in which its scoring knives 46 and 47 are disposed above the plane of the blank, the knives 46 and 47 being arranged in pairs extending at right angles to each other, as best shown in Fig. 2. Continued rotation of the rolls 7 and 8 from the position shown in Fig. 1 is accompanied by an upward movement of 50 the stops 18, thereby releasing the blank and permitting it to be projected towards the rolls 7 and 8. The movement of the blank between the rolls is accompanied by scoring of the blank between its four corners by the knives 46 and 47, the lower roll 7 being formed of somewhat yielding material if desired. The lines of scoring are indicated on the blank shown at the right in Fig. 2. As the scored blank passes from between the rolls 7 and 8, the guide 26 serves to 60 direct it between the lower scoring roll 7 and the roll 11 where adhesive is applied to the flaps 25a of the blank by the roll 27. The scored blank with the adhesive applied thereto is then conveyed by the belts 12 in a horizontal plane toward 65 the folding mechanism where its movement is arrested by the stops 23.

As best shown in Fig. 2, the stops 23 are carried by holders 48, each adjustably mounted on a shaft 49 extending between the side frames 1, 1, 70 set screws 50 serving to position the holders 48 on the shaft 49. One end of the shaft 49 has mounted thereon an arm 51 carrying at its free end a roll 52 bearing on the surface of a cam 53 mounted on a shaft 54, as shown in dotted 75

lines in Fig. 1. The shaft 54 is connected by gearing 55 to a shaft 56, see Fig. 3, which in turn is driven from the shaft 15 by means of a chain 57 at the opposite side of the frame from the gearing 55, see Fig. 2. The gaging fingers 24 which cooperate with the stops 23 are mounted on a shaft 58 extending parallel to the shaft 49, and as best shown in Fig. 1, one of the fingers 24 is pivotally connected to a link 59. The link 10 provides a yoke portion embracing the shaft 15, and carries a roll 60 bearing on the surface of a cam 61 mounted on the shaft 15. The cam 53 controlling the stops 23, and the cam 61 controlling the gaging fingers 24 are so timed that as a scored blank approaches the folding mechanism, the stops 23 are swung downwardly in front of the approaching blank, as shown in Fig. 1, thereby arresting the movement of the blank as it engages the forward corners thereof. As this occurs, the gaging fingers 24 are swung upwardly to engage the rear corners of the scored blank and accurately position it with reference to the rectangular edges of the then stationary folding forms 33, as shown at the right in Fig. 2. Downward movement of the stops 23 in front of the approaching blank is accompanied by downward movement of a pair of spaced lifters 23a, also mounted to turn with the shaft 49. The lifters 23a serve to deflect the bottom flap 25b upwardly over the folder 35 as the blank comes to rest against the stops 23, as indicated in Fig. 1.

The folding forms 33 are supported on a carriage slidably mounted between the side frames 1, 1, which carriage consists of a cross-bar 62 having its ends received in horizontal tracks 63, best shown in Fig. 1. The folder carriage is adapted to receive a reciprocatory movement between the tracks 63 from a pair of levers 64 mounted on a cross-shaft 65, each lever 64 being pivotally connected by a link 66 to one end of the cross-bar 62 of the carriage. Each lever 64 carries a roll 67 bearing on the surface of a cam 68 mounted on the shaft 15 and springs 69 bearing on the carriage serve to maintain the rolls 67 in engagement with the cam 68. Since the major portions of the cam 68 are concentric about the axis of shaft 15, the folder forms 33 are held stationary in the position shown in Fig. 2 when a scored blank is arrested and gaged by the stops 23 and fingers 24. Obviously, continued rotation of the shaft 15 from the position shown in Fig. 1 will bring depressed portions of the cams 68 into engagement with the rolls 67, thereby permitting the springs 69 to project the carriage and its folder forms 33 toward the delivery rolls 22, this action occurring after the folding operations, which will now be described.

As best shown in Fig. 4, each side flap folder 34 is pivotally mounted at 70 on a slide 71 movable at right angles to the line of travel of the envelope on a stationary support 72. A spring 73 connected at its ends between the slide 71 and the folder 34 serves to yieldingly maintain a roll 74 carried by the folder 34 in engagement with the surface of a stationary cam 75 mounted on the slide support 72. With the parts in the position shown in full lines, each folder 34 is maintained below a side flap 25a of the envelope blank 25, as the latter is brought to rest by the stops 23 in its travel forward on the secondary tapes 20, one of which is shown in Fig. 4. In other words, the folders 34 are in an inoperative position as the scored blank is registered with the then stationary folder forms 33.

Each slide 71 carrying a folder 34 provides a

roll 76 received in a track 77 formed in a cam cylinder 78 mounted at one end of the shaft 56, which as previously pointed out, is driven from the shaft 15 through the chain 57. The tracks 77 on the cam cylinders 78 are oppositely disposed, as shown in Fig. 2, so that rotation of the shaft 56 is adapted to cause the slide 71 to be moved simultaneously in opposite directions toward the line of travel of the envelope blank. It is apparent that as the slide 71 is moved to the left, as viewed in Fig. 4, the folder 34 riding on the stationary cam 75 will be swung upwardly as it advances toward the folding form 33, thereby folding a side flap 25a along the line of scoring and over the edge of the associated folding form. This action of the folders takes place simultaneously on the oppositely extending side flaps 25a.

After the folding of each side flap 25a takes place, as indicated in dotted lines in Fig. 4, the folder 35 previously referred to is operated to cause the bottom flap 25b to be folded over into engagement with the then folded side flaps 25a. As best shown in Fig. 2, the folder 35 is U-shaped in form with a horizontal portion 35a extending beneath the inclined flap 25b of the envelope blank as it comes to rest before the folding operation, the lifters 23a serving to direct the flap 25b above the horizontal folder portion 35a. The ends of the folder 35 are received in holders 79 mounted on a cross-shaft 80, one end of which carries a crank arm 80a pivotally connected to a link 81. The link 81 terminates in a yoke portion embracing the shaft 54 and carries a roll 82 bearing on a cam 83 mounted on the shaft 54. As previously pointed out, the shaft 54 also carries the cam 53 controlling the stops 23, and the cams 83 and 53 are so timed that as the folder 35 is swung to the left to fold the bottom flap 25a along its line of scoring over the end surfaces of the folder forms 33, the stops 23 will be raised, as indicated in Fig. 6.

When the stops 23 are raised, as just described, the tapes 20 exert a force on the partially folded envelope, tending to move the envelope toward the delivery rolls 22, the lower one of which is mounted on a shaft 84 carrying a gear 85 in mesh with the gearing 55, see Fig. 3. The release of the envelope by the stops 23 is also accompanied by movement of the folder form carriage toward the delivery rolls 22, the carriage controlling cam 68 permitting the springs 69 to project the carriage toward the rolls 22 just after the stops 23 are raised. Therefore, the partially folded envelope is immediately projected into the bight between the rolls 22, as indicated in Fig. 6, the folding of the flaps being completed as they pass under the folder 35, and the adhesive between the flaps being pressed closely to cause sticking as the envelope passes between the delivery rolls 22.

The return movement of the folder plate carriage following the projection of a folded blank to the rolls 22 is preceded by a slight movement of the folder forms 33 towards each other, so as to fully clear the forms from the corners of the envelope and prevent binding. While the specific mechanism for causing the shifting of the folder forms 33 forms no part of the present invention, it is indicated in Fig. 1, and will only be described briefly. As shown, each folder form 33 is mounted on a carrier 86 shiftable on the cross bar 62 of the carriage, each carrier 86 being in threaded engagement with a shaft 87 extending parallel to the cross bar 62 and rotatably

mounted thereon. One end of the shaft 87 carries an arm 88, and when the folder plate carriage is in its retracted position, as shown in Fig. 1, this arm 88 is in engagement with a stop 89. The folder plate carriers 86 are so mounted on the shaft 87 that with the arm 88 in the position shown in Fig. 1, the edges of the forms 33 are in exact register with the lines of scoring on an envelope blank as it is positioned beneath the plates by the stops 23 and fingers 24. However, as the carriage is projected toward the rolls 22 following the folding operations described above, the arm 88 leaves the stop 89, thereby permitting a spring 90 to turn the arm 88 into the position shown in Fig. 6. At this moment the carriage has reached the limit of its travel toward the rolls 22 in projecting the folded blank between the rolls, and the turning of the shaft 87 through the relatively small angle indicated causes the carriers 86 to be moved towards each other. This results in shifting the edges of the folding forms 33 from the lines of folding of the side flaps, so that a withdrawal of the forms 33 from the envelope is accomplished without any binding.

From the foregoing, it is apparent that by the present invention there is provided an improved arrangement of instrumentalities for making completed envelopes, at a high rate of production, with extreme uniformity in the folding of the envelope blank flaps with respect to the body. As a result of the correlated operations of gaging, scoring, gumming, re-gaging, and folding over forms along the lines of scoring, envelopes of a superior quality are produced, from any grade of paper, with sharp clean edges and corners of uniform character.

I claim:

1. The improvement in the manufacture of envelopes which consists in gaging a blank, scoring it between its extended flaps, gumming said flaps, regaging said blank to aline its scoring with the edges of stationary forms and folding said flaps over said forms exactly along their lines of scoring.
2. In an envelope machine, the combination with stationary forms, means for advancing a

prescored blank providing extending flaps, means for arresting the advancement of said blank, and for gaging said blank with reference to said stationary forms, of means for folding the side flaps of said blank over said forms and means for moving said forms to also cause the folding of the bottom flap over said forms. 5

3. In an envelope machine, the combination with stationary forms providing parallel straight edges, and means for advancing a pre-scored blank providing extended side flaps, a bottom flap and a seal flap, of stops for arresting the advancement of said blank and gaging members cooperating with said stops for registering the lines of scoring of said side flaps with the straight 15 edges of said forms by engagement with the junctions of said bottom and seal flaps with said side flaps, and means for folding the side flaps over said forms exactly along the lines of scoring while said blank is held stationary by said reg- 20 istering means.

4. In an envelope machine, the combination with stationary forms providing parallel straight edges, and means for advancing a pre-scored blank providing extended side flaps, a bottom 25 flap and a seal flap, of stops for arresting the advancement of said blank and gaging members cooperating with said stops for registering the lines of scoring of said side flaps with the straight edges of said forms, means for folding the side 30 flaps over said forms exactly along their lines of scoring, and means for moving said forms, together with the partially folded blank, to also cause the folding of the bottom flap over said forms exactly along its line of scoring. 35

5. The improvement in the manufacture of envelopes, which consists in gaging a blank, scoring said blank between its extended side flaps and bottom flap, gumming said flaps, re-gaging said blank to aline its scoring with the edges of stationary forms, folding first said side flaps and then said bottom flap over said forms exactly along their lines of scoring, and finally shifting the partially folded blank to complete folding down of said bottom flap into adhesive engagement with said side flaps. 40 45

VINCENT E. HEYWOOD.
